LUGGAGE TAG

Jack W. Field, 50 Riverside Drive, New York, N.Y.

Filed Jan. 11, 1965, Ser. No. 83,369

Term of patent 14 years

(Cl. D1—3)

FIG. 1 is a front perspective view of the luggage tag in an open position embodying my new design;

FIG. 2 is a rear perspective view of FIG. 1;

FIG. 3 is a front elevational view thereof in the closed position;

FIG. 4 is a bottom plan view of FIG. 3;

FIG. 5 is an elevational view taken from the left end of FIG. 3;

FIG. 6 is a fragmentary elevational view of a portion of the rear of the front portion of the tag;

FIG. 7 is a front perspective view of a modified form of the luggage tag shown in FIGS. 1 through 6 in an open position;

FIG. 8 is a rear perspective view of FIG. 7;

FIG. 9 is a front elevational view of FIG. 7 in the closed position;

FIG. 10 is a bottom plan view of FIG. 9; and

FIG. 11 is an elevational view taken from the left end of FIG. 9.

I claim:

The ornamental design for a luggage tag, as shown and described,
